UNITED STATES PATENT OFFICE.

SUMNER A. DUDLEY, OF TAUNTON, MASSACHUSETTS.

SHUTTLE.

1,277,882.

Specification of Letters Patent. Patented Sept. 3, 1918.

Application filed October 29, 1917. Serial No. 198,951.

To all whom it may concern:

Be it known that I, SUMNER A. DUDLEY, a citizen of the United States, residing at Taunton, in the county of Bristol and State 5 of Massachusetts, have invented a new and useful Improvement in Shuttles, of which the following is a specification.

This invention relates to certain new and useful improvements in a shuttle, and more 10 particularly to the eye for guiding the yarn, and it has for a principal object to provide an eye of plastic material which will be long-lived and efficient in use.

Further, the invention resides in the provision of an eye which is reversible and consequently capable for use either in a right 15 or left hand shuttle.

Another aim of the invention is found in the coöperation between the eye and the 20 shuttle which permits of the eye being easily threadded without danger of the yarn becoming dislodged by reason of the fact that the drag of the yarn is such that the wood of the shuttle prevents the yarn from coming out 25 of the eye.

In the drawings

Figure 1 is a fragmentary top plan view of a shuttle embodying the present invention.

30 Fig. 2 is a side elevation thereof.

Fig. 3 is a transverse section on line 3—3 of Fig. 2, and

Fig. 4 is a detailed perspective of the eye.

Referring more in detail to the accompanying drawing the numeral 1 designates the body of the shuttle having the threading slit 2 and the communicating delivery eye passage in which is disposed the guiding eye 3. This eye is preferably made of porcelain, 35 as the life of this plastic is much longer 40 than that of metal in this particular adaptation.

The eye is provided with a pair of peripheral seats 4 with either of which is engaged the eye securing pin 5, one seat being engaged by the pin in a right hand shuttle and the other seat being engaged by said pin when the eye is employed in a left hand shuttle so that the eye is reversible and consequently, universally adaptable for both 50 types of shuttle.

Each end of the eye is countersunk or formed with a central concentric depression 6 which has a lateral outlet over the edge of 55 the cylindrically shaped body of the eye, the peripheral portion of the eye connecting the

outlets of the end depressions also being depressed inwardly from the major periphery, as at 7. This peripheral depression 7 extends the full length of the eye body and substantially a quarter way around, the lower longitudinal edge being formed with a thread slot 8 which also extends the full length of the eye body and radially to the center. In practical use, the depressed portions of the eye are preferably polished or given a glazed finish to facilitate the drawing of the thread thereover when threading the eye, while the remaining surface of the body is left in the rough finish as is depicted 60 clearly in Fig. 4, which rough periphery better grips the interior wall of the eye passage of the shuttle.

The eye is arranged in the eye passage so that the upper edge of the peripheral depression 7 is immediately above the entrance of the threading slit 2, this latter entering the eye passage substantially midway between the upper and lower sides thereof. The peripheral depression therefore coöperates with the opposing inner wall of the eye passage in forming a downwardly directed extension of the threading slit which merges into the radially thread slot 8, the latter being disposed vertically in the 70 shuttle.

Being secured against displacement by the pin 5, the inner end of the eye abuts a raised portion or platform 9 of wood, being an integral part of and cut from the body of 90 the shuttle, said platform being cut away, as at 10, to receive the inner end of the eye whereby the latter is protected and housed by the platform. This platform extends above the lower opened side of the thread 95 slot 8, as depicted in Fig. 3, and supports the yarn in its travel from the bobbin to the eye so that the yarn is secured against passing out through the opened side of the slot 8 and back into the threading slit 2. Having a central end depression 6 in each end, the bottom of the depression is thereby spaced from the platform to afford easy passage of the yarn into the thread slot of the eye during the threading operation, this 100 being true in either mounting of the eye.

It will therefore be noted that the eye is reversible, acting efficiently in either the right or left hand shuttle. The glazed finish of the depressed portions of the eye facilitates the passage of the yarn thereover and between the peripheral depression and the 110

wood of the shuttle. Through the particular mounting and disposition of the eye the drag of the yarn is such that the wood of the shuttle will prevent the same from being accidentally displaced. An important feature resides in the formation of the eye from porcelain which is very desirable as the life is much longer than if it were made of metal, and since the eye is well protected by the body of the shuttle there is little danger of breaking the plastic body, the term "porcelain" being herein used to include analogous substances as is obvious.

Having thus described my invention, what I claim as new and desire to secure by Letters Patent is—

1. A shuttle having an eye passage, a threading slit opening thereinto above its bottom, and a platform extending horizontally across the inner end of the eye passage and above the bottom of the latter for guiding the thread, and a thread-guiding eye arranged within the eye passage and formed with a vertical radial thread slot which com-

municates through its periphery with the 25 threading slit of the shuttle below the platform whereby the latter serves as a means for holding the thread up in the thread slot of the eye against displacement.

2. A yarn guiding eye for shuttle, comprising a cylindrical body having a longitudinally extending radial slot opening through each end and the periphery, the periphery being depressed on one side of the slot in a circumferential direction and throughout its length, said depressed portion being concentric to the remainder of the periphery, the ends of the slot flaring outwardly, said flared ends terminating short of the circumference, the body being 49 glazed within said flared ends.

In testimony whereof I have signed my name to this specification in the presence of two subscribing witnesses.

SUMNER A. DUDLEY.
